CONTAINER WASHING MACHINE

August Holmquist, Hooperston, Ill., assignor to
Food Machinery Corporation, San Jose, Calif.,
a corporation of Delaware

Application May 19, 1932, Serial No. 612,313

6 Claims. (CL 141—7)

This invention relates to an apparatus for washing cans, bottles or various other types of containers and is especially adapted to the washing of the commercial open end cans known as 5 "Sanitary cans".

During the shipment and storage of the cans of commerce they come into contact with dust and dirt of various kinds so that it is highly desirable that they be washed and cleansed before 10 food products are placed therein.

In the operation of canning machinery certain speeds of operation are desirable and necessary in order to take care of each day's oncoming products, so that any device for washing cans 15 must be such as will handle the cans fully as fast as other machines in the factory, and in order to do this successfully the machine must essentially be continuous in operation.

It is also desirable in a machine for this class 20 of work that the operation be reduced to its simplest expression so that no complicated mechanism becomes necessary and that the moving elements are simply and substantially made.

A general outline of the construction of this 25 can washer contemplates a rotary carrier enclosed in a substantially water tight housing; means for feeding cans successively to the rim of the rotary carrier; means positioned in a groove in the bed of the rotary carrier for spraying cleansing liquid into the cans which are positioned on the rotary carrier in an inverted position; means for removing the cleansed cans from the rotary carrier; means for driving the rotary carrier whereby the drive may be applied from any desired angle; means for controlling the 30 operative speed of the rotary carrier to suit factory conditions and the speeds of associated machines as well as other features that will be referred to in the specification following.

It is therefore an object to provide a machine 40 for washing containers wherein the containers are moved continuously and in succession through the machine.

It is a further object of the invention to provide 45 a machine for washing cans wherein the cans are washed in an inverted position so that they will be self draining and the residue washed therefrom will fall away by gravity assisted by the washing liquid.

It is also an object of the invention to provide 50 a washing device having liquid spray for projecting liquid into the inverted cans to remove adhering débris.

It is also an object of the invention to provide 55 a washing device wherein the spray means is

housed in a groove below the level of the can support on the rotary carrier and the cans are moved over it during the spraying operation.

It is also an object of the invention to provide a machine for washing containers wherein the drive means may be swung around a half circle 5 relative to the machine so that power can be applied from any desired direction.

It is also an object of the invention to provide a means of drive wherein the speed of the machine may be regulated to suit any factory conditions and speed of operation.

With such objects in view as well as other advantages which may be inherent in the invention, it is understood that the several necessary elements, parts and combinations constituting the same may be varied in their proportions, placement and general arrangement without departing from the scope and nature of the invention.

In order to make the invention more clearly 20 understood there are shown in the accompanying drawings, somewhat diagrammatically, means and mechanism for placing the same in concrete form, without limiting the improvements to the particular construction shown.

Figure 1 is a plan of the machine.
Figure 2 is a vertical section of Figure 1 taken on approximately the line 2—2 of Fig. 1.

Figure 3 is a detail sectional view of the discharge chute.

Figure 4 is a perspective of the spray device.

The numeral 1 represents the housing, supported on suitable legs 2. The housing 1 comprises the top shell section and a base section 3, the base section carrying a depending central hub 4 in which is securely positioned a short vertical shaft 5, on the lower end of which is a friction drive disc 6, and on the upper end of which is positioned the washing rotary carrier 7. Positioned on the hub 4 is the drive supporting bracket 8, carrying the drive shaft 9, the friction pinion 10, the adjusting block 11, the adjusting screw 12 and the drive pulley 13. The bracket 8 is revoluble about an arc of 180 degrees as is indicated by the dotted line on Figure 1 45 so that the machine may be connected to power from any desired angle. When the drive is set to the desired position the bracket 8 is locked in position by the set screw 14 impinging on the rim 15 of the base member 3.

The washing rotary carrier 1 has an annular groove 16 in which is positioned the spray pipe 17, which extends nearly around the entire circle. The pipe 17 enters at 18 Fig. 1 and ends at 19. The pipe has perforations 20 along its surface 50

to form the sprays for projecting the cleansing liquid into the cans.

21 represents the feeding chute which is positioned substantially centrally of the machine 5 so as not to consume space outside thereof. The cans are given a quarter twist as they enter their positions on the rim of the rotary carrier 7 where they stand open end down as they are advanced over the stationary spray pipe 16. The cans are 10 subjected to the cleansing action of the sprays for nearly a complete circle, or substantially the length of the pipe 17, and are swept off the rotary carrier by the arm 22 and tipped into the chute 23 which conveys them to further use in the 15 canning line. 24 represents the cans, and for clearness only two are shown, and at the left of Figure 2 is clearly seen how the spray jets enter the open ends of the inverted cans and thoroughly cleanse the interiors which, on account of being 20 inverted are self draining. The accumulation of cleansing liquid is conveyed from the machine by the pipe 25 and may if desired lead to a tank and screening device to be used over again, or if plain water is used it may be conveyed to the 25 drain so that each can is washed with clean unused water which would be supplied by a suitable pump to give the necessary pressure to produce sprays of sufficient intensity to do efficient cleansing. The pipe 17 is held in position by the bracket 30 26 bolted to the side of the housing 1. By manipulating the hand crank 27 on the adjusting screw 12 the friction pinion 18 will be traversed across the friction disc 6 and thereby the rotary speed of the rotary carrier is regulated to suit the speed 35 with which cans must be delivered to the other machines in the canning lines.

In order to hold and maintain the cans in position on the rotary carrier rim guide rails 28 are provided held in place by suitable hangers 29.

40 What I claim as new and desire to secure by Letters Patent is:

1. An apparatus for washing containers comprising in combination, a housing, a rotary carrier in said housing, an annular groove in the face of said carrier, means for positioning containers on said carrier over said groove, a spray pipe having a fixed support and partly positioned in said groove out of contact with the positioned containers on said carrier and adapted to project spray against said containers to cleanse the same, with means for removing said containers from said carrier.

2. An apparatus for washing cans comprising in combination, a housing, a rotary carrier in said housing, a vertical shaft carrying said rotary carrier, means for giving rotation to said rotary carrier, means for positioning cans with open ends down on said rotary carrier, a groove in said rotary carrier below the can level, a stationary spray means in said groove to project cleansing liquid into the cans thereabove and means

for removing the accumulated spray liquid from said housing.

3. An apparatus for cleansing cans comprising a rotary carrier for conveying cans through a predetermined path, means for positioning cans on said rotary carrier with the open ends down, a groove in said rotary carrier under said positioned cans, and stationary spray means in said groove out of contact with said cans for projecting cleansing liquid into the inverted cans to cleanse them.

4. An apparatus for washing cans or the like comprising a rotary carrier, means for driving the rotary carrier, means for feeding cans successively to said rotary carrier, said rotary carrier including a circular rim for supporting the cans with their open ends down, means for guiding cans onto said rotary carrier rim and maintaining them radially adjusted thereon, an annular groove in said rim, a spray pipe located in said groove out of contact with the cans supported by the rim and held against movement, means conveying washing material to said spray pipe and means for removing washed cans from said carrier.

5. An apparatus for washing open end cans or the like, comprising a closed housing with a central top opening, a rotary carrier within said housing and means for feeding open end cans to said rotary carrier through the said central top opening in said housing and depositing them open end downward on the rim of said rotary carrier, a groove in said rotary carrier rim open at the top, a stationary spray pipe located in said groove out of contact with the cans on said rim, means entering said casing to convey washing solution to said spray pipe between the inlet and discharge points for the cans, means for rotating said rotary carrier and means for discharging washed cans from said rotary carrier at a point removed from the inlet.

6. An apparatus for washing open end cans or the like, comprising a closed housing having a central top opening, a rotary carrier positioned in said housing and having a flat rim to support open end cans with their open ends downward, a curved can chute entering the central top opening of said housing and delivering cans radially to the flat rim of said rotary carrier, a can discharge device adjacent said delivery chute for removing washed cans from the outer edge of said rotary carrier rim, a groove in said rotary carrier rim, a stationary spray pipe positioned in said groove, a solution conveying pipe connecting with said spray pipe through said housing at a point between the placing of cans on said rotary rim and the discharge of cans from said rotary carrier rim, and means for rotating said rotary carrier.

AUGUST HOLMQUIST.
